ADJUSTABLE THERMOSTAT SWITCH

John Leonard Schwartz, Philadelphia, Pa., assignor to Clarence A. Rossmann, J. Leonard Schwartz, and Hugo Engelhardt, a copartnership doing business as The Philadelphia Thermometer Company, Philadelphia, Pa.

Application April 26, 1946, Serial No. 665,164

5 Claims. (Cl. 200—141)

1

This invention relates to adjustable thermostats, and particularly to the increase in accuracy thereof.

In an application Serial Number 611,819, filed August 21, 1945, I disclosed an improved adjustable thermostat of high efficiency and utility. It is a feature of that application to provide a double bored thermometer tube in one bore of which an adjustable contact member in the form of a wire electrode was slidably mounted to establish one side of the line of the circuit to be controlled, and the other bore contains a permanent contactor completing the circuit through the instrument. It has been found that sometimes certain features of inaccuracy attached to apparently identical thermostats made according to that and other disclosures, which it is the principal object of this invention to obviate.

Among the objects of the invention are: to provide an improved thermostat; to provide a thermostat in which a series of substantially identical instruments will have predetermined substantially identical high degrees of accuracy; and to provide other objects and advantages as will become more apparent as the description proceeds.

In the accompanying drawings forming part of this disclosure:

Fig. 1 represents a longitudinal section of the thermostat of said application as modified by the invention herein.

Fig. 2 represents a fragmentary section on an enlarged scale through the thermostat of Fig. 1 with a "made" contact relation between a wire electrode and the end of a mercury column.

Fig. 2A represents a fragmentary section similar to part of Fig. 2 with a "broken" contact relation between a wire electrode and the end of the mercury column.

Fig. 3 represents a transverse section taken through the thermostat of Fig. 1 on line 3—3 of Fig. 2.

Fig. 4 represents a fragmentary section through a modified form of a barrel of an adjustable thermostat, showing a modified form of an adjustable electrode wire therein.

Fig. 5 represents a transverse section through the barrel shown in Fig. 4, on line 5—5 thereof.

The thermostat shown in Fig. 1, as purely illustrative of an application of the invention, comprises a barrel or double bored shank 10 containing the two capillary bores, respectively the inactive bore 11, and the active bore 12. The latter communicates directly with the mercury 13 in the bulb 14. Both bores preferably com-

2

municate with the enlarged upper chamber and mercury reservoir 15 containing the actuating mechanism formed of the supporting panel 16 seated on a median partition 19, and on which panel is rotatably journaled a threaded shank 17, carrying the armature 18, by the rotation of which a travelling electrode wire 20 is suitably caused to be vertically adjusted in the bore 12. Rotation is effected by the rotatable annular magnet 21. A suitable connection is established between the adjustable wire electrode 20 and one terminal 7 of the thermostat, and a wire 22 extends from the other terminal 8 into the bore 11 from which to complete the circuit. A transverse embedded electrode wire or connector 23 extends from the inactive bore 11 to the active bore 12. Any of the modified forms of thermostat shown in that application may equally well be used.

It has been discovered that with apparently identical processing, the degrees of accuracy between apparently identical instruments were sometimes measurably different, and this also pertains to the results from other types of thermostats, as shown, for instance, in U. S. Patent No. 2,108,338, to Juchheim, granted February 15, 1938, with a barrel having a single bore and an axially movable wire in that bore for the making and breaking of the circuit through the mercury. After considerable research, it has been discovered that the reason for the fluctuations or variations in responsiveness arises from the differences in the location of the contact-making end of the wire electrode relative to the walls of the bore. It has been found that there are two untoward happenings when the free end of the wire electrode is out of the substantially coaxial center of the bore and in contact or substantial contact with the walls of the bore. One unfortunate happening is the more or less permanent lodgement of mercury between the electrode and bore wall by a species of capillarity manifested usually as an upswelling bulge asymmetrical of the miniscus of the mercury. This is a variable happening as it can sometimes be dislodged by shock or vibration and sometimes it cannot, and as it distorts the end of the column of mercury in the bore, its adverse effects on readings can be imagined. The other undesirable characteristic attaching to asymmetrical dislodgement of the free end of the wire electrode in the bore is because of the fact that the bore is a capillary bore, within which the end of the mercury forms a miniscus, and after substantial stabilization for a certain time interval the mercury seemingly becomes more or less attached to the

walls of the bore, especially where the convex surface thereof intersects and contacts the bore wall. Pursuant to this effective relative attachment, if this is the term for the phenomenon, slight changes in the temperature incident upon the mercury 13 in the bulb 14, accompanied by a slight change in the volume of mercury instantaneously present in the bore 12 and bulb 14, is manifested initially by a mere change in the profile of the miniscus. This profile change depends for its sense upon the direction or sense of temperature change, and the curvature, i. e., the relative convexity or concavity of the miniscus, changes in the center without actual movement at the edge thereof in contact with the bore walls. Of course, continuance of changed temperature causes actual movement of the entire miniscus axially of the bore, but for sensitive control purposes, the first faint breathing of the miniscus is the only activity by which to secure control functions. It will be readily seen that under such conditions of breathing without axial shift of the entire miniscus, that the sensitivity of the thermostat would vary as a function of the distance the wire electrode end is from the axial center of the bore and, therefore, of the miniscus. It is, therefore, the primary object of this invention to cause the electrode wire to be centered in all of its positions in the bore, whether elevated or depressed therein, while at the same time avoiding any stoppage in the bore which might act as a trap to mercury.

In carrying out the invention in an illustrative form, the wire electrode 20 is formed into a sliver point as at 24. Close to the point, say, illustratively, from $\frac{1}{8}$ " to $\frac{1}{4}$ " therefrom, or thereabouts, a rounded bend or crimp 25 is made in the wire, of such external extent radially of the bore and of the axis of the wire, as to enable guided bearing on a wall of the bore. At a short axial distance therefrom, say, illustratively at about $\frac{1}{4}$ ", preferably in the same plane containing the wire 20 and the crimp 25, a second crimp or bend 26 is formed, preferably extending radially from the wire in a direction opposite to crimp 25, and of such external extent radially of the bore and of the axis of the wire as to enable guided bearing on the wall of the bore opposite to that surface juxtaposed to crimp 25. The wire electrode, preferably formed of tungsten or the like may be given the crimps in any desired way, but illustratively a pair of cooperating complementary dies are formed to give the wire the slight indentations or crimps shown in such enlarged scale in Figs. 2 and 3. With the wire electrode 20 slid endwise into the bore 12, the point 24 thereof will be held in centered relation by the oppositely disposed crimps or bends 25 and 26, with the range of possible deviations of the point from the exact axis outlining a very small area. It will be observed in this connection that movement in the plane of the crimps diametrical of the bore is limited by the clearance between the outer edges of the crimps and the surface of the bore. Movement bodily in a line transverse to the plane of the wire and crimps is also limited by this same clearance projected transversely against the bore surface. At the same time, there is preferably such relatively loose engagement as to minimize adverse frictional effects.

With the wire electrode 20 disposed in the bore 12 with the point 24 thereof centered, and with the centered relation maintaining during movements of the electrode axially of the bore, it will be observed that the expanded mercury 13 from the bulb 14 rising in the bore 12, with the upper

end forming a miniscus 27 will ultimately cause the terminus 24 of the electrode to penetrate or at least to establish contact with the substantial center of the miniscus. As shown in Fig. 2, the center of the miniscus is axially appreciably closer to the point 24 than the edge 28 of the miniscus where it contacts the surface of the bore 12. The contact closes the circuit through the instrument and through any desired amplifying or relay system, to actuate any desired control or indication, but as this latter forms no part of the present invention no part of the control circuit, as such, is disclosed.

After the circuit has been made by contact of the substantial center of the miniscus with the end 24 of the electrode 20, in due course there will develop a slight change in the temperature incident upon the bulb 14, which will manifest itself in its initial, almost its incipient stage, as a downward "breathing" of the miniscus. By this preliminary responsiveness, without any relative movement of the edge 28 of the miniscus and the surface of the bore 12, which it intersects, the convexity of the miniscus decreases and it becomes relatively more flattened, as shown in Fig. 2A. This withdraws the center of the miniscus from its circuit-making contact with the point 24 and the circuit is broken. Thereafter, by the operations of the device with which it is associated or the like, the temperature incident upon the bulb 14 may increase. This again causes elongation of the miniscus until the substantial center thereof again contacts the point 24 of the electrode 20 without disturbing the peripheral line 29 of the edge of the miniscus, and the circuit is again made.

It will be apparent that as the point 24 of an uncrimped wire departs from a concentric relation in the bore and moves closer to the surface of the bore 12, and this is the actual result of previous forms of electrodes used in any form of thermostat known to me, with the degree of departure from the axial center being unpredictable, the sensitivity of the instrument decreases. The particular degree of decrease of sensitivity varies between supposedly identical instruments at datum temperatures, and may also vary between supposedly identical instruments with changes of setting, and it is, therefore, highly desirable that the point 24 be accurately centered at all times and this is accomplished with the formation of the guide surfaces 25 and 26 of Fig. 2. In this connection, it will be seen that for one reason or another it is quite possible for the mercury 13 to rise in the bore 12 or otherwise to fill the bore (as from the reservoir formed in the enlarged chamber 15), until the mercury has immersed the crimps 25 or 26. It is a feature of great importance that even such immersion has no mercury-trapping results, as the crimp is formed in the body of the wire only, and as this is of extreme thinness, the tendency of mercury globules to engage between the wall of the bore 12 and one or the other of the crimps 25 or 26 is so minimized as to constitute no particular hazard. This is in contrast to any separate non-integral wire guides which might be attached to the wire, which would inevitably present such cross sectional area as either to form an actual valve or trap of more or less permanency for mercury disposed above it, or would manifest such trapping tendency as to effectively trap varying quantities at varying times with a consequent upset of the accuracy of the instrument.

It has been mentioned that the invention is

of value in any form of thermostat and the only limitation is that the wire electrode be disposed in a capillary bore of an instrument and that it be movable therein axially of the bore, and that mercury be arranged to rise and fall in the bore relative to the end of the wire as an incident of some change of condition effective to move the mercury. Thus, in Fig. 4 there is disclosed a fragmentary section of the barrel of the thermostat shown, for instance, in said U. S. Patent No. 2,108,338. The barrel, illustratively designated as 28, has a capillary bore 30, in which mercury 13, having a minuscus 27, is disposed. The electrode wire 31 has a splinter point 32, for contacting the mercury, and may either have the same crimps as are shown in Fig. 2, or a slightly modified form of crimps by which the lowermost crimp 33, adjacent to the point 32, leads, preferably directly across the line of the wire to the complementary crimp 34, so that adjacent to the point 32 the wire is guided on both sides of the center. If desired, the crimps 33 and 34, instead of being complementally continuous, may be axially spaced for a slight distance to reduce bending of the wire and to reduce the axial proximity of the crimps to each other to reduce any tendency such proximity might engender to trap or hold mercury after an immersion therein. A third crimp 35 may be formed in the wire 31 in axially slightly spaced relation to the pair of crimps 33 and 34, as a stabilizing guide crimp. It will be seen that from the standpoint of positive guide, the crimp arrangement of Fig. 4 offers more lateral bearing area and guiding function than the two oppositely disposed crimps of Fig. 2. On the other hand, the stability and positive guidance from the pair of axially spaced crimps of Fig. 2 have been found for all practical purposes to be satisfactory.

The cheapness, efficiency and positive operation of the invention and the enhanced accuracy of the system will be clear.

Having thus described my invention, I claim:

1. A thermostat comprising a barrel having a capillary bore, mercury in the bore, a movable electrode wire disposed in the bore, said wire having a plurality of lateral bends in such relative

angularity as to guide the wire in the bore to maintain its substantial concentricity therein.

2. A thermostat comprising a barrel having a capillary bore, mercury in the bore, a movable electrode wire disposed in the bore, said wire having lateral bends in axially spaced relation and angularly so spaced as to guide the wire in the bore to maintain its substantial concentricity therein.

10 3. A thermostat comprising a barrel having a capillary bore, mercury in the bore, a movable electrode wire disposed in the bore, said wire having lateral bends in axially and angularly spaced relation to guide the wire in the bore to maintain its substantial concentricity therein, said bends being in a common plane containing the wire.

20 4. A thermostat comprising a barrel having a capillary bore, mercury in the bore, a movable electrode wire disposed in the bore, said wire having lateral bends in axially spaced relation to guide the wire in the bore to maintain its substantial concentricity therein, said bends being respectively oppositely projected out of the line of 25 the wire.

5. A thermostat comprising a barrel having a capillary bore, mercury in the bore, a movable electrode wire disposed in the bore, said wire having lateral bends in axially spaced relation to 30 guide the wire in the bore to maintain its substantial concentricity therein, said bends being respectively oppositely projected out of the line of the wire and lying in a common plane with the wire.

35 JOHN LEONARD SCHWARTZ.
